UNITED STATES PATENT OFFICE.

SAMUEL E. STOKES, OF PHILADELPHIA, PENNSYLVANIA.

CONTROLLING DEVICE FOR ELEVATORS.

SPECIFICATION forming part of Letters Patent No. 453,450, dated June 2, 1891.

Application filed November 15, 1890. Serial No. 371,542. (No model.)

To all whom it may concern:

Be it known that I, SAMUEL E. STOKES, a citizen of the United States, and a resident of Philadelphia, Pennsylvania, have invented 5 certain Improvements in Controlling Devices for Elevators, of which the following is a specification.

The object of my invention is to so connect the hand-wheel of a cab of an elevator with 10 the controlling mechanism that the two ends of the connecting rope, chain, or band will be stationary, and the slack caused by the raising or lowering of the cab will be taken up by the counterbalance-weight of the cab, 15 as fully described hereinafter.

In the accompanying drawings, Figure 1 is 20 a view illustrating my invention. Figs. 2 and 3 are perspective views of details of the device shown in Fig. 1, and Figs. 4 and 5 are views illustrating a modification of the stringing of the controlling-rope.

A is the elevator-well, and B the cab.

The usual elevating-ropes are omitted from 25 the drawings in order to avoid confusion; but they pass over the usual sheaves and are connected to any suitable lifting mechanism.

The counterbalance-weight L in the present 30 instant carries a sheave l, which is suspended by a loop in the rope a. This rope is attached to a fixture at one end and to the car at the other end and passes over a sheave C at the top, as clearly shown in the drawings. It will be understood that this counterbalance-weight 35 may be geared to the car in any manner depending upon the character of car used.

D is the controlling mechanism, in the present instance in the form of a valve.

I is the controlling-rope, connected to the 40 operating mechanism J on the car, and at the opposite end to a lever or wheel D on the valve-shaft. As shown in Fig. 1, this rope passes down from the car, around a sheave H at or near the base of the elevator, and up over a sheave carried by the counterbalance-

weight L and down to the controlling mechanism. Thus it will be seen that as the elevator is raised or lowered the counterbalance-weight will be moved in proportion thereto, and consequently the slack in the controlling-rope will be taken up or let out by this movement of the counterbalance-weight.

In Fig. 4 the stringing of the rope is changed, it passing up over a sheave H² and around the sheave H' on the counter-weight, up over a sheave H³, down under the sheave D' to the 55 controlling mechanism. The stringing of the rope will vary, according to the character of the elevator and the space it occupies; but it will be understood that the controlling-rope must be geared in proportion to the gearing 60 of the counterbalance-rope, as readily understood by those skilled in the art.

I claim as my invention—

1. The combination, in an elevator, of the car, the counterbalance-weight therefor, the 65 controlling mechanism, the operating device on the car, and a rope connecting the operating device and the controlling mechanism and passing around a bearing or pulley on the counterbalance-weight, whereby the slack in 70 the rope is taken up or let out as the car is raised or lowered, substantially as set forth.

2. The combination, in an elevator, of the car and counter-weight, the operating device on the car, valve-controlling mechanism, ropes 75 connecting the valve-controlling mechanism with the operating device, with a take-up pulley carried by the counterbalance-weight and applied to the rope at a point between the operating device and the valve, substantially 80 as and for the purpose specified.

In testimony whereof I have signed my name to this specification in the presence of two subscribing witnesses.

SAMUEL E. STOKES.
